UNITED STATES PATENT OFFICE.

JACOB H. WUNDERLICH, OF BALTIMORE, MARYLAND, ASSIGNOR TO NATIONAL CASKET COMPANY, OF NEW YORK, N. Y., A CORPORATION OF NEW YORK.

COLLAPSIBLE CRATE FOR CASKETS.

1,169,100.

Specification of Letters Patent.

Patented Jan. 18, 1916.

Application filed October 21, 1914. Serial No. 867,731.

To all whom it may concern:

Be it known that I, JACOB H. WUNDERLICH, a citizen of the United States, residing at Baltimore, in the State of Maryland, have 5 invented certain new and useful Improvements in Collapsible Crates for Caskets, of which the following is a specification.

This invention relates to an improved construction of collapsible crate and has particular reference to a crate in which caskets or coffins may be packed for shipment and transportation.

Manufacturers of caskets having numerous sales and supply branches located at 15 cities distant from the factory have experienced considerable annoyance and expense in shipping caskets from the factory to the sales and supply branches. It has been the custom to pack each casket in a wood box 20 of sufficient size to entirely inclose it, and these boxes after reaching their destination, are opened, and the caskets removed, and the empty inclosing boxes stored or piled one upon another awaiting their return, in 25 an empty condition, to the factory. The large size of these empty boxes cause considerable annoyance in the storage space required and the size and weight are the source of considerable expense to effect their return 30 shipment as empties.

The present invention therefore has for its object to provide an improved construction of collapsible crate, particularly designed for the shipment of caskets, which 35 shall be of less weight than a complete shipping box; that will be rigidly braced and held while in extended or in a collapsed condition; that will afford ample protection to the casket against dust, dirt and moisture 40 and which, when empty, may be collapsed so as to occupy a minimum space during storage or shipment as empties.

With these and other objects in view, the invention is illustrated in the accompanying 45 drawings wherein,—

Figure 1, shows the improved crate extended and in side elevation. Fig. 2, illustrates one end of the cover in top plan. Fig. 3, shows an end of the cover in bottom or inverted plan. Fig. 4, illustrates the extended crate in vertical longitudinal section,—the section being taken on the line 4—4 of Fig. 5. Fig. 5, shows the extended 50 crate in end elevation. Fig. 6, illustrates a

vertical cross-sectional detail through the 55 crate at one end,—the section being taken on the line 6—6 of Fig. 1. Fig. 7, shows the crate in side elevation and in a collapsed condition. Fig. 8, illustrates the same in vertical longitudinal section. Fig. 9, shows 60 an enlarged detail of a fragment of the cover and side of the collapsed crate partly in side elevation and partly in section, and Fig. 10, illustrates an enlarged fragmentary detail of one of the brace blocks and brace 65 bars on the interior of the crate.

The crate comprises a bottom section 11, a top section 12; a flexible wall 13, connected to the top section and extending into the bottom section and a cover 14 normally resting on the top section.

The bottom section is preferably made in a skeleton form, for the purpose of reducing weight, and in the present instance consists of two longitudinal bars 15, which are rigidly connected by a plurality of spaced-apart cross-bars 16 and extend from one end of the crate to the opposite end. These cross-bars have their ends resting on top of the longitudinal bars so that the lower sides 75 or surfaces of the cross-bars will have position in a plane above the bottom surface of the longitudinal bars, thereby enabling said longitudinal bars to serve as a skid on which the crate may rest and be pushed endwise 80 along a floor or over the sill of a car door or onto a truck or wagon without damage to the cross-bars.

A rectangular frame is rigidly attached to and extends vertically above the cross-bars 90 and said frame has two edge-wise placed side bars 17, and two edge-wise placed end-bars 18, that connect the side bars.

It will thus be understood that the bottom section includes the rectangular frame; the 95 cross-bars and the longitudinal skid bars, all rigidly connected together. The top section 12, is the part that is free to be moved upward or downward relative to the stationary bottom section 11. The top section of the 100 crate also has the form of a rectangular frame in that it has two vertical edge-wise side bars 19, that are rigidly connected at their ends by end bars 20.

The rectangular bottom section 11, and the 105 rectangular top section 12, of the crate have preferably the same dimensions, both as to length and width so that the top section will

fit down and rest upon the bottom section, when in a collapsed condition and be flush on the inside and also outside with said bottom section.

5 A wall of flexible material 13, has its upper edge secured around the inside of the top section and extends down into the bottom section and is spread horizontally over the cross-bars 16, so as to form a bottom covering as well as a flexible vertical side wall which latter is secured to the inside of the bottom section.

10 Each side bar 17, of the bottom section 11, is provided on its inner side with two brace bars 21, each of which is pivoted by one end to the side bar at 22, and the ends of the two brace bars that are pivoted to the same side bar preferably have their pivoted ends adjacent to each other, as best seen in Figs.

15 20 and 8, of the drawings. Each side bar 19, of the top section has a brace block 23, at each end thereof and on its inner side, and each brace block is provided with an end notch 24. When the top section 12, of the crate is raised with respect to the bottom section, the free ends of the brace bars 21, may be swung upwardly and seated in the notches 24, of the brace blocks, as clearly shown in Figs. 4

25 30 and 10, of the drawings, so that said brace bars will not only aid in sustaining the top section in an elevated position, but will also brace said top section against lateral, or lengthwise movements with respect to the bottom section. The length of the brace bars is such that they may be swung down inside of the bottom section and rest upon the cross-bars 16, when the crate is in the collapsed condition, as shown in Fig. 8, of

40 45 the drawings. The lower section 11, of the crate also carries four standard bars 25, one at each corner of the crate. These bars each have one end pivoted at 26, to the outer side of a side bar 17,—the pivot points being adjacent the ends of said side bars, so that the free ends 27, of the standard bars may be swung up at the outer side of the side bars 19, of the top frame. Each stand-

50 55 ard bar 25, in the present instance has a notch 28, at one vertical side edge and also has a notch 29, at the other vertical side edge. When in the vertical sustaining position, as shown in Fig. 1, the notches 28, of the standard bars each engage a headed member 30, that is carried on the side bar 19, but when the crate sections are collapsed and bars 25, are lowered, each notch 29, will engage a headed member 31, that are also carried on the side bar 19, of the top section frame, as shown in Figs. 7 and 9, of the drawings. The purpose of these notches and headed members will presently be explained.

60 65 By reference to Figs. 1 and 5, of the drawings it will be noted that side bar 17, of

the bottom section has a plurality of vertically-projecting pins 32, extending upwardly from its upper edge and that bar 19, of the top section is provided with recesses or sockets 33, see Fig. 1, which receive the pins 70 32, when the two sections are collapsed. Obviously the arrangement of pins and recesses may be reversed with respect to the bars, it being desirable to have pins on one bar to engage recesses on the other bar to 75 lock the two frames together against lateral movement when said frames are collapsed, as in Fig. 7. The cover 14 which rests on the top section 12, of the crate also has two side bars 33, two end bars 34, that connect the side bars; a plurality of spaced-apart cross bars 35, that also connect the side bars and whose upper surfaces are flush with the upper edges of the side bars and two spaced longitudinal bars 36, that extend lengthwise 85 and directly beneath the cross-bars. These longitudinal bars 36, have position in a horizontal plane above the lower edges of the side and end bars of the cover, so that when the cover is seated on top of the movable 90 crate section these bars 36, will rest upon the top edge of said section.

The side bars 33, of the cover have notches 37, that extend upwardly from their lower edges near each end, as shown in Figs. 1 and 95 3, of the drawings, so that when the cover seats on the top section the upper free ends 27, of the standard bars 25, will project into said notches 37, and be locked against disengagement from the headed members 30. 100

It will thus be seen that when the top section of the crate is elevated, the brace bars 21, by engaging the notches 24, in the blocks 23, both of which are on the interior, will lock the two sections against lateral and 105 longitudinal displacement while the standard bars 25, on the exterior will serve mainly to sustain the weight of the top section and the cover 14, and the latter in turn will hold said standard bars with their notches 29, 110 in engagement with the headed members 30, thereby making a rigid structure while the crate is in the expanded condition.

Suitable blocks 38, are provided on the under side of the cover to engage the inner 115 side of the top frame and thereby aid in holding the cover rigidly in place.

By referring to Figs. 3 and 9 of the drawings it will be noted that the side bars 33, of the cover are also provided at their 120 inner surface with inclined notches 40, which latter, when the crate is collapsed receive the free ends of the standard bars 25, as shown in Fig. 9, and thereby hold the notches 29, of said two bars in engagement 125 with the headed members 31. Thus the standard bars 25, secure the top and bottom sections together. A flexible covering 41, is provided on the cover at the under side of cross-bars 35, to keep out dust and moisture. 130

When the crate is in use suitable bolts 42, serve to hold the cover on the movable section.

From the foregoing explanation it will be understood that to collapse the crate, presuming it to be in the extended condition shown in Figs. 1 and 4, the cover section 14, will be removed so as to disengage the bars 25, and also to permit access to the brace 10 bars 21, on the interior. The brace bars will then be released from the brace blocks and swung down into the bottom section. The standard bars 25, will then be released from headed members 30 and turned down- 15 ward, thereby allowing the movable section to be lowered. During the lowering, the flexible wall 13, will be tucked inwardly and the top section will then be lowered onto the bottom section. As the two sec- 20 tions come together the pins 32, on the one section will enter the recesses 39, of the other section so as to bring the vertical outer and inner surfaces of the two sections flush with each other, and also to aid in locking 25 the sections against lateral displacement. When the two sections are close together, the bars 25, will be swung over to engage the notches 29, with headed members 31, which will further lock the two sections together. 30 The cover section will then be placed on the movable section and the free ends 27, of the bars 25, will enter the edge notches 40, in the side bars 33 of the cover so as to bind 35 said bars and protect them against side blows during shipment. Bolts 42, will then secure the cover section on top of the movable section and the crate will then have a knockdown condition and occupy a minimum space and at the same time will be rig- 40 idly secured together for shipment.

Having described my invention what I claim is,—

1. A collapsible crate having in combination, a bottom section provided with a rec- 45 tangular frame; standard bars each having one end pivoted to the outer side of said bottom-section frame so as to swing up to a vertical position and each standard pro- 50 vided at its free end with a side notch 28; a top section provided at its side and near its end with projecting pins 30, which en- 55 gage said side notches on the standard bars to sustain said top section; two brace bars 21, each of which has one end pivoted to the inner side of said bottom-section frame

and the free ends of said two braces adapted to swing upwardly to oppositely-inclined positions and said free ends engaging the said top section when the crate is expanded.

2. A collapsible crate having in combina- 60 tion, a bottom section provided with a rec- tangular frame; standard bars 25, having one end pivoted to the outer side of said bottom-section frame so as to swing to either a vertical or an inclined position, and each 65 standard provided near its free end with two side notches one 28, being in one edge and the other 29, in the opposite edge; a top section provided on its outer side near each end with a projecting pin 30, for the 70 engagement of one notch on said standard when the latter is swung to a vertical position to sustain said top section, and said top section also provided intermediate its ends with additional projecting pins 31, for the 75 engagement of the other notch on the standard when the latter is swung to an inclined position to secure the top and bottom sec- 80 tions together when the crate parts are in collapsed position.

3. A collapsible crate having in combina- 80 tion, a bottom section provided with a rec- tangular frame; standard bars each having one end pivoted to the outer side of said bottom-section frame so as to swing up to 85 a vertical position and each standard bar provided at its free end with a side notch 28 below its upper free extremity 27; a top section provided at its side and near its ends with projecting pins 30, which en- 90 gage said side notches on the standard bars and sustain said top section when the latter is raised; means connecting between the bottom section and top section when the crate is expanded to secure longitudinal rigidity 95 between the two sections; and a cover resting on the top section and having down- projecting side bars provided on their inner lower edge with notches 37, which when the crate is expanded receive the said upper free 100 extremities of said pivoted standards, whereby said cover prevents the standard-notches disengaging from said pins on the top sec- 105 tion.

In testimony whereof I affix my signature 105 in presence of two witnesses.

JACOB H. WUNDERLICH.
